United States Patent Office.

EDWARD S. STIMPSON, OF MILFORD, MASSACHUSETTS, ASSIGNOR
TO DUTCHER TEMPLE COMPANY, OF SAME PLACE.

Letters Patent No. 90,133, dated May 18, 1869.

IMPROVEMENT IN LUBRICATING TEMPLES FOR LOOMS.

The Schedule referred to in these Letters Patent and making part of the same.

To all persons to whom these presents may come:

Be it known that I, EDWARD S. STIMPSON, of Milford, in the county of Worcester, and State of Massachusetts, have invented a new and useful Improvement in Roller-Temples for Looms for weaving cloth; and do hereby declare the same to be fully described in the following specification, and represented in the accompanying drawings, of which—

Figures 1 and 2 are vertical sections of two descriptions of the Dutcher roller-temples, showing my improvement as applied to them, the object of such being to enable the toothed roller; and its supporting-spindle and cap, to be lubricated, or supplied with oil at proper times, and especially to introduce such oil directly against or in close proximity with that end of the roller which is borne against the projection of the cap by the cloth, while the weaving of it may be in the process of being effected.

The temple shown in fig. 1 has its spindle screwed into the trough-standard, but the temple exhibited in fig. 2 has its spindle inserted in sockets, *x y*, one of which is made in the temple-trough standard, and the other in the ear, or projection of the cap, such sockets being closed at their outer ends, so as to hold the spindle in place.

In carrying out my improvement, I form, in the projection of the cap, and so as to lead to the spindle and to the next adjacent end of the roller, a passage, by which oil, after having been poured into such passage, shall be conveyed by it to the spindle and to the next adjacent end of the roller, without first going lengthwise through the bore of the spindle.

In the drawings—

- A* denotes the toothed roller;
- B*, the trough;
- C*, the cap;
- a*, the standard of the trough; and

b, the projection of the cap.

The spindle of the roller is shown at *D*, the oiling-passage in the projection of the cap being represented at *E*. This passage may lead into a groove, *c*, made either transversely, or longitudinally, or otherwise, in the spindle, in order that the oil may be carried by such groove into the bearing or bore of the roller.

I am aware, that in the patent, No. 82,684, dated October 6, A. D. 1868, and granted to Lucius Briggs, the centre-pin of the roller is represented as extending beyond the trough-head, or standard, and provided with an oil-passage leading into the extension, and thence axially into the pin, and finally, transversely out of the pin near the middle of the roller.

This invention differs entirely from mine, and does not accomplish one important result sought to be attained by mine, viz, the oiling of that end of the roller which, by the draught of the cloth, is borne against the projection of the cap while the weaving of the cloth may be in progress.

It is between the projection of the cap and the end of the roller which is next to it, that the friction generated is the greatest, and therefore, such is the place where the oil is most needed.

What, therefore, I claim as my invention, or improvement in the roller-temple for looms, is—

The arrangement of the oiling-passage *E* in the projection *b* of the cap *C* of such temple, so that oil, after having been poured into such passage, shall be conveyed by it both to the spindle and to the next adjacent end of the toothed roller, before going through the bore of the roller, the whole being substantially as specified.

EDWARD S. STIMPSON.
